(57) **CLAIM**

The ornamental design for an instrument module, as shown and described.

DESCRIPTION

FIG. 1 is a front perspective view of an instrument module in accordance with an embodiment;

FIG. 2 is a rear perspective view of an instrument module in accordance with an embodiment;

FIG. 3 is a front elevational view of an instrument module in accordance with an embodiment;

FIG. 4 is a rear elevational view of an instrument module in accordance with an embodiment;

FIG. 5 is a left side elevational view of an instrument module in accordance with an embodiment;

FIG. 6 is a right side elevational view of an instrument module in accordance with an embodiment;

FIG. 7 is a top view of an instrument module in accordance with an embodiment;

FIG. 8 is a bottom view of an instrument module in accordance with an embodiment; and,

FIG. 9 is a front elevational view of an instrument module in accordance with an embodiment showing additional environmental information.

The broken lines shown in the figures represent portions of the instrument module that form no part of the claimed design.
